UNITED STATES PATENT OFFICE

ROE P. HENDERSON, OF SPRINGFIELD, OHIO, ASSIGNOR TO THE SPRINGFIELD METALLIC
CASKET COMPANY, OF SPRINGFIELD, OHIO, A CORPORATION OF OHIO

DESIGN FOR A CORNER PLATE FOR A BURIAL CASKET

Application filed September 17, 1932. Serial No. 44,974. Term of patent 3½ years.

To all whom it may concern:

Be it known that I, ROE P. HENDERSON, a citizen of the United States, residing at Springfield, in the county of Clark and State of Ohio, have invented a new, original, and ornamental Design for a Corner Plate for a Burial Casket, of which the following is a specification, reference being had to the ac-

companying drawing, forming part thereof.

The figure is a front elevation of a corner plate for a burial casket, showing my new design.

I claim:

The ornamental design for a corner plate for a burial casket, as shown.

ROE P. HENDERSON.
